UNITED STATES PATENT OFFICE.

RICHARD S. ARTHUR, OF NEW YORK, N. Y.

SOUND RECORDING AND REPRODUCING MACHINE.

1,357,936.

Specification of Letter's Patent. Patented Nov. 9, 1920.

Application filed October 29, 1917. Serial No. 199,217.

To all whom it may concern:

Be it known that I, RICHARD S. ARTHUR, a citizen of the United States of America, and a resident of New York city, in the county of New York and State of New York, have invented new and useful Improvements in Sound Recording and Reproducing Machines, of which the following is a specification.

10 The objects of this invention are to secure improved motor or actuating means for a talking machine or the like, to enable the same to occupy little space, and be wound at a convenient point; to secure an improved governor by which the movement is simply and efficiently regulated, and which governor can be easily adjusted; to secure an improved sound box and means for resiliently engaging its stylus with the record; to provide improved means for stopping and starting the motor and for returning the stylus of the sound box to initial position; to enable records to always properly fit the record carrier or support, and to obtain 25 other advantages and results as may be brought out in the following description.

Referring to the accompanying drawings in which like numerals of reference indicate the same parts throughout the several views, 30 Figure 1 is a plan of a machine embodying my invention;

Fig. 2 is a side elevation with parts broken away for greater clearness;

Fig. 3 is a view similar to Fig. 1 with the 35 horn removed and other parts broken away;

Fig. 4 is a sectional view on line 4—4 of Fig. 3;

Fig. 5 is a sectional view on line 5—5 of Fig. 3;

40 Fig. 6 is a plan of the governor;

Fig. 7 is an underneath plan of the sound box, and

Fig. 8 is a sectional view on line 8—8 of Fig. 2 showing modified means for frictionally mounting the record upon the record carrier.

In the specific embodiment of the invention illustrated in said drawings, the reference numeral 1 indicates a suitable base plate 50 or support upon which is mounted a sound box 2 near one end and a governor 3 near the other end. The sound box has a vibrating lever 4 which projects toward the governor and upon which is mounted a stylus 5 near the outer end of said lever. Above the stylus is a rotatable record carrier 6 ac-

tuated by a motor the spring 7 of which extends along one side of the base plate and curves around the sound box 2 across the end of the base plate with suitable winding 60 means at the opposite side thereof. Means also operable from this same side of the base plate as said winding means are provided for removing the stylus from the record and for returning the sound box to its original 65 or starting position.

Preferably the end portion 8 of the base plate upon which the governor is mounted is bent upward at an angle to the plane of the rest of said plate upon which the sound 70 box is mounted. A post or bracket 9 projects upward from said plate, preferably from the part thereof where the end portion 8 bends up and adjacent one side edge of said plate, see Figs. 1, 2 and 3, and affords bearings at its top for several parts, as will be described. A spring mandrel 10 is secured at one end to a lower part of said post, as by a nut 11, said mandrel extending adjacent the side edge of the plate 1 and 80 bending near the end of the plate to extend longitudinally of the end edge to the opposite side edge of the plate where it is supported by a boss 12 projecting from the plate. At this last-mentioned end of the spring mandrel, the same is preferably made with a rotatable stud 13 (see Fig. 5), said stud having one end inserted in the stationary part of the mandrel, the end of which is socketed for the purpose, and having its 90 other end extending through the boss 12. Displacement of the stud from the stationary part of the mandrel is prevented by a transverse pin 13^a in the stationary part of the mandrel which takes into a peripheral 95 groove 13^b in the stud near its inner end. A handle or crank 14 is provided for the outer end of the stud, whereby it may be rotated with respect to said boss and stationary part of the mandrel. Any suitable 100 ratchet means may be employed to permit rotation of the stud in one direction and prevent its rotation in the other direction, and this means I have shown as a helical spring 15 which fits close upon said stud so as to grip it and has one end made fast to the boss 12 of the base. Rotation of the stud to wind up the motor tends to unwind the ratchet spring 15 and consequently the stud may rotate, but attempted rotation of the 110 stud in the other direction causes the spring 15 to wind up and grip the stud thus hold-

ing it secure. Between the stationary part of the mandrel and the boss 12, I preferably provide a hole 16 transverse of the stud into which one end of the motor spring 7 is inserted so that rotation of the stud will wind up said spring. Said motor spring 7 is coiled around the mandrel 10 to the other end thereof adjacent the post 9 and there engages a worm wheel 17 rotatably mounted upon the mandrel. By winding up the motor spring at one end by the crank 14 it will tend to unwind at its other end and thus rotate the worm wheel 17.

In mesh with, and, as shown, above the worm wheel 17, is a worm 18 preferably on one end of a shaft 19 which carries at its other end the record carrier 6. I have shown the shaft 19 and worm 18 integral and supported in bearings 20, 21 on the upper end 20 of the bracket 9 (see Fig. 8), although any other equivalent structure might be employed. While the record carrier 6 may be driven from its shaft 19 in any suitable manner, I preferably make the record carrier rotatably loose upon the shaft and provide a 25 spring 22 which has one end made fast to the shaft and the other end fast to the record carrier, this resilient drive being more particularly shown and described in my co-pending application Serial No. 195,023 filed October 6, 1917.

The governor 3 preferably employed is at the sloping end 8 of the base plate and is driven from the shaft 19 upon which the record carrier is mounted. Said governor comprises a shaft 23 journaled at one end in a suitable bearing 24 in the sloping portion 8 of the base plate and projecting upward past the record carrier shaft 19 into a bearing 25 for its other end at the top of the post 9, the upper part of the shaft being a worm 26 in mesh with a worm wheel 27 upon the record carrier shaft 19. Upon the lower part of the governor shaft 23, is a disk 28 or equivalent supporting means upon which are pivoted weighted arms 29, 29 adapted to be thrown outward by centrifugal action in braking, and these arms rotate within a cylindrical housing 30 upon the base plate, 50 the inner wall of which housing preferably slopes inwardly downward toward the base plate for purposes hereinafter described. The weighted arms 29, 29 are pivoted, as at 31, 31 upon the disk 28, see Fig. 6, preferably diametrically opposite each other and have at their outer sides brake shoes 32, 32 adapted to engage said cylindrical surface of the inner wall of the housing when the arms 29, 29 are swung downward. For 60 holding the governor arms 29, 29 normally inward, I have shown a spring 33 secured at its opposite ends to said arms and passing through a transverse hole in the said governor shaft 23, although any other equivalent means could be employed.

As stated above, the inner wall of the housing 30 slopes or tapers toward the end of the governor shaft which has its bearing in the base plate, and therefore shifting the governor shaft longitudinally, so that the 70 arms 29, 29 will have a greater or less distance to be thrown outward into engagement with said wall, will adjust the governor and thus the speed of the machine. In order to accomplish this, a spring is employed to 75 slide the governor shaft longitudinally in one direction and an adjusting screw is provided to force it in the other direction against the power of said spring. More specifically, I have shown the end of the governor shaft projecting through the base plate, where it is engaged by a leaf spring 34 to force it upward, and in the top of the bearing in the bracket 9 for the upper end of the governor shaft is a screw 35 engaging 80 the end of the shaft longitudinally, all as clearly shown in Fig. 4. Other means for adjusting the governor arm and the tapered wall of the housing with respect to each other could be employed, however. 90

The sound box 2 preferably used in connection with my improved machine is pivoted to oscillate so the stylus can follow the groove in the record, and is also pivoted so the stylus may be swung into engagement 95 with the record and swung away from the record as will next be described. The body portion 36 of the sound box is annular, with a projecting neck 37 to fit loosely in the lower end of an amplifier or horn 38, and 100 contains a diaphragm 39 between holding rings as usual. Support for the sound box is obtained by a yoke 40 which extends diametrically of the body portion on the opposite side thereof from said neck 38 and 105 has ears 41, 41 at its opposite ends to which the body portion 36 is pivoted by its peripheral edges as at 42. At the middle of the yoke 40 is a pivot pin 43 which projects into a suitable socket 44 in the base plate 1, and 110 by virtue of this pin the sound box may oscillate in its plane, while by virtue of the pivoting of the sound box in the yoke 40 said sound box may be tilted to engage and disengage the record. 115

At the edge of the body portion 36 of the sound box next the record carrier and preferably midway between the points of pivoting of the yoke 40 to said body portion, is a fulcrum 45 the knife edge of which is toward the base plate 1. Seated upon this fulcrum is a lever 4, which is secured at one end to the diaphragm and projects at its other end beyond the body portion of the sound box beneath the record carrier so that the stylus 5 carried on said end may engage the record. In order to hold the lever 4 against its fulcrum 45, I have shown screws 46, 46 at opposite sides of said lever, which enter the body portion of the sound box with their 125 130

heads or washers thereat underlying marginal portions of the lever. It is through this lever 4 that vibrations are transmitted between the stylus and diaphragm of the 5 sound box.

Preferably the sound box is resiliently tilted to normally engage the stylus with the record, and for this purpose a leaf spring 48 is shown secured at one end to the yoke 10 40 for convenience by the pivot pin 43, the other end of this leaf spring extending to the edge of the sound box opposite the fulcrum 45 for the lever 4. As shown the leaf spring projects into a staple 49 or the like at the 15 under side of the body portion of the sound box, the normal tendency of the spring being to pull down upon said staple and thereby tilt the sound box upon its yoke 40 to press the stylus 5 upward toward the record.

20 For tilting the sound box against the force of the spring 48 to disengage the stylus from the record, a rotatable rod 50 is mounted at its ends in suitable bearings 51, 51 on the base plate and extends across the 25 sound box above the same and between its neck 37 and the stylus, having a suitable knob 52 at one end by means of which said rod may be turned. A spring 53 between said knob and the adjacent bearing 51 provides 30 sufficient friction to hold the rod in whatever position it is turned to. Upon this rod 50, over the body portion of the sound box, is a cam 54 adapted to engage the said body portion and swing it downward 35 when the rod is turned in one direction, and thus the stylus can be released from the record when desired. Means are also provided for swinging the sound box back to its original or starting position by means of this 40 rod 50, and this means I have shown as a sloping cam surface 55 upon the top of the body portion of the sound box adjacent said rod adapted to be engaged by a pin or finger 56 on said rod when the rod is turned to 45 release the stylus from the record and wedgingly force the sound box through the desired arc. It may be noted, however, that the cam 54 operates somewhat in advance of the finger 56 so as to disengage the stylus 50 from the record before the finger engages the cam surface 55 to force the stylus back to starting position. Also on said rod 50 is 55 a brake arm 57 at one end of the record carrier adapted to engage the same and stop it when the rod is turned for releasing the stylus from the record.

Turning the rod 50 in one direction therefore stops the machine by means of the brake arm 57, removes the stylus from the record 60 and returns it to initial position, while turning said rod in the other direction starts the machine by releasing the brake from the record carrier and the cam 54 and finger 56 from the top of the sound box so that the

same is tilted by its spring 48 to press the 65 stylus against the record.

Initial position of the stylus with respect to the record is determined by suitable stop means which limit swinging of the sound box by engagement of the finger 56 with 70 the sloping cam surface 55. I have illustrated such means by a stop 58 (see Fig. 3) projecting upward from the base plate and adapted to engage a peripheral projection 59 of the sound box which preferably 75 carries the staple 49. This stop also serves to limit swinging of the sound box in the other direction by engagement with the adjacent end of the yoke 40.

In the machine of the cylinder type, such 80 as I have illustrated, I preferably employ records without backing or reinforcing, and therefore it becomes necessary to provide some means for compensating for their shrinkage or expansion due to atmospheric 85 conditions in making them always fit properly upon the record carrier. In Figs. 3 and 4 I have shown for this purpose a layer 60 of felt or the like upon the record carrier 6, the resiliency of such a layer compensating 90 for any slight differences in the record 61. In Fig. 8 I have shown springs 62 upon the other surface of the record carrier for the same purposes, said springs extending longitudinally and three or more being employed 95 suitably distributed around the periphery. I have shown these springs held in place by screws 63 at the end of the record carrier, although obviously they might be otherwise secured. 100

Obviously detail modifications and changes may be made in manufacturing my improved machine without departing from the spirit and scope of the invention, and I do not wish to be understood as limiting myself 105 except as required by the following claims when construed in the light of the prior art.

Having thus described the invention, what I claim is,

1. The combination with a support, of 110 a substantially U-shaped yoke pivotally mounted thereon, a sound box pivoted between the arms of said yoke to tilt upon a substantially diametric axis, and a leaf spring between the base of said yoke and 115 said sound box normally tilting the latter, one end of said spring being fixed and the other in sliding engagement.

2. The combination with a sound box mounted to rotate in its plane and to tilt 120 upon a substantially diametric axis, of means for simultaneously rotating and tilting said sound box.

3. The combination with a yoke, a sound box body pivoted in said yoke, a lever fulcrumed on the edge of said body at substantially right angles to its line of pivoting, said lever secured to the diaphragm at one 125

- end and having a stylus at the other end, and a spring between said yoke and body portion adapted to tilt the sound box in said yoke.
5. The combination with a sound box pivotally mounted to rotate in its plane, of a sloping cam surface on said sound box arranged transverse to radial lines thereof, and means for engaging said cam surface to
- 10 turn the sound box.
5. The combination with a sound box pivotally mounted to rotate in its plane, of a sloping cam surface on said sound box arranged transverse to radial lines thereof, a finger engaging said cam surface to turn the sound box, and means for swinging said finger.
6. The combination with a sound box pivotally mounted to rotate in its plane, of a sloping cam surface on the top of said sound box arranged transverse to radial lines thereof, a rotatable rod above the sound box adjacent said cam surfaces, and means on said rod for engaging said cam
- 20 surface to turn the sound box.
7. The combination with a sound box mounted to rotate in its plane and to tilt upon a substantially diametric axis, and a spring normally tilting said sound box, of a sloping cam surface on said sound box arranged transverse to radial lines thereof, members adapted one to engage the sound box to tilt it and the other to engage said cam surface to turn the sound box, and
- 30 means for operating said members simultaneously.
8. The combination with a sound box mounted to rotate in its plane and to tilt upon a substantially diametric axis, and a
- 40 spring normally tilting said sound box, of a sloping cam surface on the top of said sound box arranged transverse to radial lines thereof, a rotatable rod above said sound box, and members on said rod for engaging
- 45 the sound box to tilt the same and engaging its said cam surface to turn the sound box.
9. The combination with a sound box mounted to rotate in its plane and to tilt upon a substantially diametric axis, and a
- 50 spring normally tilting said sound box, of a sloping cam surface on the top of said sound box arranged transverse to radial lines thereof, a rotatable rod above said
- sound box, a cam on said rod for engaging the sound box to tilt the same, and a finger on said rod adapted to engage said cam surface to turn the sound box.
10. The combination with a sound box mounted to rotate in its plane and to tilt upon a substantially diametric axis, and a spring normally tilting said sound box, of a sloping cam surface on the top of said sound box arranged transverse to radial lines thereof, a rotatable rod above said sound box, and means for operating said member to tilt the sound box sufficiently in advance of turning it to disengage the stylus from the record.
11. The combination with a record carrier, a motor for driving said record carrier, a tilting sound box, and a spring normally tilting said sound box, of a rotatable rod, a cam on said rod adapted to engage said sound box to tilt it against the power of said spring, and a brake on said rod for stopping the motor.
12. The combination with a record carrier, a motor for driving said record carrier, and a sound box pivotally mounted to rotate in its plane, of a sloping cam surface on the top of said sound box arranged transverse to radial lines thereof, a rotatable rod above the sound box adjacent said cam surface, a finger on said rod for engaging said cam surface to turn the sound box, and a brake on said rod for stopping the motor.
13. The combination with a record carrier, a motor for driving said record carrier, a sound box mounted to rotate in its plane and to tilt upon a substantially diametric axis, and a spring normally tilting said sound box, of a sloping cam surface on the top of said sound box arranged transverse to radial lines thereof, a rotatable rod above said sound box, means for operating said member to tilt the sound box sufficiently in advance of turning it to disengage the stylus from the record, and a brake on said rod for stopping the motor.
